UNITED STATES PATENT OFFICE.

WILLIAM A. BRYANT, OF COLLINSVILLE, ALABAMA, ASSIGNOR OF TWO-THIRDS TO MARSHALL M. NICHOLSON AND JAMES L. REEVES, BOTH OF SAME PLACE.

HORSE-DETACHER.

SPECIFICATION forming part of Letters Patent No. 392,946, dated November 13, 1888.

Application filed May 23, 1888. Serial No. 274,851. (No model.)

To all whom it may concern:

Be it known that I, WILLIAM A. BRYANT, a citizen of the United States, residing at Collinsville, in the county of De Kalb and State of Alabama, have invented certain new and useful Improvements in Horse-Detachers, of which the following is a specification, reference being had therein to the accompanying drawings, in which—

10 Figure 1 represents a plan view of my improved detaching device applied to the shafts of a vehicle; Fig. 2, a side elevation of one end of the singletree; Fig. 3, a longitudinal sectional view of the same; Fig. 4, a plan view 15 of the same; Fig. 5, a side elevation of a portion of one of the shafts, showing a releasing device for the holdback-strap used when the invention is applied to vehicles with shafts; Fig. 6, a section on line $x-x$, Fig. 2; Fig. 7, a 20 detail view of a bushing inserted in ends of the ferrules.

The invention has relation to that class of inventions which are designed to instantly release a horse from a vehicle should the animal 25 become frightened and unruly, thereby avoiding all danger from runaway accidents, as will be more fully hereinafter set forth.

The invention relates particularly to that 30 class of devices wherein a strap or cord is attached to the spring-actuated trace-securing bolts or pins and extended back to within convenient reach of the driver of the vehicle, whereby the driver may at a moment's notice release the traces by withdrawing the bolts, as 35 will presently appear.

Referring to the accompanying drawings by letter, A designates a pair of shafts or thills of the ordinary construction, and B a singletree pivoted thereto in the usual manner and 40 provided with metallic ferrules C C at its ends, the ferrules being provided with sockets in which the ends of the singletree fit.

The ferrules are recessed or hollowed out at 45 their outer ends, and in these recesses work the spring-actuated trace-bolts D D, the rear ends of the bolts being guided by the concentric passages a a in the ferrules, and their forward ends working in bushings b b, inserted in the ends of the ferrules. The ferrules are each 50 provided with longitudinal slots d and a hole,

c, the latter of which permits any water or sand that may get into the recesses in the ferrules to run off.

E designates a U shaped clevis or cuff applied on the ends of the ferrules to hold the traces on the bolts D. These cuffs each consist of the concentric rings e e', the former of which fits over the shouldered end of the ferrule and the latter serves to prevent the trace from slipping off the trace-bolt, the two rings 60 being connected at their tops by a rounded integral connection, e'', and the ring e being provided with a short radial projection, e''', which projects into the aforesaid slot d and prevents the cuff from turning on the ferrule. The trace-bolts D each have preferably formed integral with it a pin or post, D', which extends up through the longitudinal slot d in the ferrule and has attached to its upper end a flat spring-catch, F, and the operating-string G, the string 65 passing through an eye or staple, f, secured near the outer or free end of the said spring-catch. By means of the springs G the trace-bolts may be readily drawn back, so as to release the traces, and when so drawn back the 70 spring-catch F (the normal tendency of which is to press downward) will automatically engage with lugs f', formed on the upper sides of the ferrules, and hold the bolts in such position until released by hand or by the aid of the 75 string.

It will be observed from Figs. 3 and 4 that the flat spring-catches completely cover the slots d, thereby preventing water and dirt from getting into the ferrules. As a further protection, I may employ metallic caps H, which may either be cast integral with the ferrules or secured thereto, the inner ends of these caps being slotted for the passage of the operating cords or wires G. The spring-catches F may 80 be disengaged from the lugs f' by simply pulling upon the cords G or by hand. The instant the catches are released the coiled springs h force the bolts D forward through the eyes in the end of the traces. 95

It will be observed from Figs. 3 and 7 that the bushings b are notched at b' for the reception of the pins D' when the bolts D are projected.

It will readily be observed from the forego- 100

ing that my device is applicable to any of the ordinary singletrees now in use, and that all its working parts are effectually protected from injury. It will also be observed that all its 5 parts may be readily put together and removed at will.

The letter I designates a portion of a strap that may be connected to the operating-cords G and extended back to within convenient 10 reach of the driver of the vehicle.

In Fig. 5 is represented a device which is secured on the under side of the shafts, and is employed for the purpose of automatically releasing the holdback-strap when the traces 15 are released. The device consists of a plate, J, perforated at or near its ends for the passage of the securing-bolts i. Formed integral with this plate near its forward end is a hook, K, which projects rearwardly and downwardly, 20 as shown. Formed on this plate immediately to the rear of the hook K are two ears, j j, between which is pivoted a depending jaw, L, which is kept pressed normally forward against the end of the hook K by means of a flat spring, 25 M, the free end of which presses against a thumb, m, formed on the said jaw L. The adjacent portions of the hook K and jaw L are preferably slightly beveled, as shown, to facilitate the insertion of the ring of the hold 30 back-strap.

It will be observed that when the traces are

released and the animal moves forward the depending jaw L will be forced open, and the holdback-strap released also.

Having thus fully described my invention, 35 what I claim as new, and desire to secure by Letters Patent, is—

1. The combination of the singletree and ferrules, the said ferrules being slotted, as described, and the cuffs E on the ends of ferrules, 40 the bushings b, inserted in the ends of ferrules, the spring-actuated bolts D, the pins D', attached to the said bolts and extending through the slots in the ferrules, the spring-catches adapted to engage with the lug f' on ferrules, 45 and the operating-cords, substantially as described.

2. The combination, with the singletree, ferrules placed on the ends thereof, the said ferrules being slotted at d and perforated at c, of 50 the bushings b, the cuffs E on ends of ferrules, the spring actuated trace-bolts D, the pins D', the spring-catches adapted to engage the lugs f', the operating-cords, and the slotted caps H, slotted at their inner ends, substantially as 55 described.

In testimony whereof I affix my signature in presence of two witnesses.

WILLIAM A. BRYANT.
